INVENTOR:

By Charles L. McBride,
By Almon Hall, Atty.

UNITED STATES PATENT OFFICE.

CHARLES L. McBRIDE, OF TOLEDO, OHIO.

GLOVE-STRETCHER.

SPECIFICATION forming part of Letters Patent No. 766,372, dated August 2, 1904.

Application filed April 18, 1904. Serial No. 203,596. (No model.)

To all whom it may concern:

Be it known that I, CHARLES L. McBRIDE, a citizen of the United States, residing at Toledo, in the county of Lucas and State of Ohio, have 5 invented certain new and useful Improvements in Glove-Stretching Machines; and I do declare the following to be a full, clear, and exact description of the invention, such as will enable others skilled in the art to which it appertains 10 to make and use the same, reference being had to the accompanying drawing, and to the figures of reference marked thereon, which forms a part of this specification.

My invention relates to a glove-stretching 15 device, known to the trade as a "laying-off" board, for use by manufacturers of gloves.

My invention is designed to furnish a form over which the glove after the parts are sewed together may be slipped and which will by the 20 movement of the form automatically stretch the fingers as may be required. I attain these objects by means of the devices and arrangement of parts herein described and shown, and 25 illustrated in the single figure of the accompanying drawing, which is a perspective view of my device, the dotted lines illustrating the position of the form when it is inclined away from the operator and ready to receive the glove to be stretched, the solid lines representing the form in upright position with the 30 tips of the finger-plates hereinafter referred to separated.

In the drawing, 1 is a base-plate adapted to be secured to a table. Projecting upwardly 35 from the top of the plate near each side margin is a lug 2, to which lug is pivotally secured, as at 3, a finger-plate 4, formed at its upper end to conform to one-half of the interior of an unstretched glove minus the 40 thumb, the stretching of the thumb portion being performed by a separate operation. 5 is a corresponding finger-plate opposed to the plate 4 and formed so that the two plates when 45 their upper ends or tips are brought together exactly conform to and fill the fingers of the gloves to be stretched. The plate 5 is pivotally secured to the plate 4, as at 6, about midway between the upper and lower ends of the plates. This pivotal connection is so 50 arranged and adjusted that the plate 5 tilts upon

the pivot 6 in such manner that the tips of the finger portions of the plate may be swung toward each other or asunder.

Projecting upwardly from the top of the plate 1 near its rear margin is a rest 7, the top of which forms a stop for the plate 4 when it is tilted backwardly at an angle of about forty-five degrees. Projecting upwardly from the top of the base-plate on the side of the finger-plates opposite from the rest 7 is a block or plate 8, which is adjustable horizontally toward and away from the finger-plates by means of set-screw 9, which passes through a slightly-elongated hole 10 in the horizontal portion of the plate 8. This arrangement permits the movement of the plate horizontally when the set-screw is loosened, and by means of the set-screw the plate is clamped at exactly the required distance from the swinging finger-plates. The inner face of this block or plate lies in the path of the lower end of the plate 5 when this latter plate is swung with its mate upon the pivot 3.

The operation of my device is as follows: The plate 1 being properly secured to its table 75 so that the plate 8 is nearest to the operator and the parts being adjusted for the size of gloves to be operated upon, the two plates 4 and 5 are tilted forwardly into inclined position, as indicated by the dotted lines in the 80 drawing, and the glove to be stretched is slipped over the upper end of the plates 4, 5, the finger portions of which are now in closed relation and which readily slip into the fingers of the glove. The operator now swings 85 the stretcher upon the pivot 3 into upright position. As the plates 4, 5 swing forwardly the lower end of the plate 5 comes in contact with the block or plate 8, pressing the lower ends of the two plates together and swinging 90 the upper ends of the two plates asunder upon the pivot 6, thus separating the finger-tips and stretching the fingers of the glove. The extent of the swing of the plate 5 upon its pivot 6 may be regulated by the position of the 95 block or plate 8.

Having described my invention and its operation, what I claim, and desire to secure by Letters Patent, is—

1. In a glove-stretcher, a pair of corre- 100

sponding opposing finger-plates, pivotal connections between said plates, a pivotal support for the pair of plates, and means actuated by the swing of the pair of plates upon their pivotal support for throwing the tips of said finger-plates into open or closed relation.

2. In a glove-stretcher, a base, a finger-plate pivotally secured thereon, another corresponding finger-plate pivotally secured in opposition to the first-mentioned finger-plate, a stop for supporting the pair of finger-plates in inclined position with their tips in closed relation, and another stop which opens said tips when the pair of finger-plates is 15 swung upon their pivotal support.

3. In a glove-stretcher, a finger-plate, a pivotal support for said plate, a corresponding opposing finger-plate, pivotal connections between said two plates upon which their tips 20 may be swung into open or closed relation,

and a stop adapted to engage said second-mentioned plate and to swing the same upon its pivotal connection with the first-mentioned plate.

4. A glove-stretcher comprising a base, a finger-plate pivotally mounted upon the base, a corresponding opposing finger-plate pivotally secured to the first-mentioned plate, a stop for the support of the pair of plates in inclined position, and an adjustable stop adapted and arranged to engage one of said plates and to throw the tips of said plates into open relation.

25 In testimony whereof I affix my signature in presence of two witnesses.

CHARLES L. McBRIDE.
